CALCULATING MACHINE

Richard Hollerith, Jr., Upper Montclair, Richard S. Dormer, Hanover, and Terry L. Barner, East Orange, N.J., assignors to Monroe Calculating Machine Company, Orange, N.J., a corporation of Delaware

Filed July 5, 1960, Ser. No. 61,251

Term of patent 14 years

(Cl. D64—11)

FIG. 1

FIG.2

FIG.3

FIG.4

FIG.5

Fig. 1 is a front perspective view of a calculating machine showing our new design;

Fig. 2 is a top plan view thereof;

Fig. 3 is a right side elevational view, the side opposite thereto being similar in appearance;

Fig. 4 is a front elevational view; and

Fig. 5 is a rear elevational view.

The essential features of the design reside in the portions shown in solid lines on the drawing.

The dot-dash line illustration of the roll of tape shown in Figs. 1-5, inclusive, is for illustrative purposes only.

We claim:

The ornamental design for a calculating machine, as shown and described.
